[57] CLAIM

The ornamental design for exercise cycle, as shown and
described.

DESCRIPTION

FIG. 1 is a left side elevational view of an exercise cycle
showing my new design;

FIG. 2 is a top plan view thereof;

FIG. 3 is a front elevational view thereof;

FIG. 4 is a rear elevational view thereof; and,

FIG. 5 is a bottom plan view thereof.

The right side elevational view is a mirror image of the
left side elevational view of FIG. 1.

FIG 3

FIG 4

FIG 5
